(57) **CLAIM**

I claim the ornamental design for a light emitting diode lamp, as shown and described.

DESCRIPTION

FIG. 1 is a top perspective view of a light emitting diode lamp of the present invention;

FIG. 2 is a bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The evenly spaced broken lines shown in the drawings illustrate portions of the light emitting diode lamp and the unevenly spaced broken lines in the drawings define the limits of the claimed design. All broken lines form no part of the claimed design.
